UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,846, dated October 24, 1893.

Application filed September 19, 1893. Serial No. 485,911. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of floral ornaments placed equidistant and each comprising a large floral or bouquet-like figure, cornucopia shaped figures springing from the stem of the latter figure, and scroll ornaments inclosing the cornucopia shaped figures, as represented in the accompanying drawing.

15 In the upper or border portion of the design, the lower portion of the scroll ornaments curve in reverse directions and terminate in cornucopia like figures and between the adjacent ornaments are finial like figures.

What I claim is—

1. The design for wall paper herein shown and described.

2. In the design for wall paper the border herein shown and described.

Witness my hand this 15th day of September, 1893.

CHARLES BOOZE.
